UNITED STATES PATENT OFFICE.

JACOB WILLIAM KOHN, OF NEWARK, NEW JERSEY.

ALARM-LOCK.

SPECIFICATION forming part of Letters Patent No. 308,678, dated December 2, 1881.

Application filed May 3, 1884. (No model.)

To all whom it may concern:

Be it known that I, JACOB WILLIAM KOHN, a citizen of the United States, residing at Newark, in the county of Essex and State of New Jersey, have invented certain new and useful Improvements in Alarm-Locks; and I do hereby declare the following to be a full, clear, and exact description of the invention, such as will enable others skilled in the art to which it app pertains to make and use the same, reference being had to the accompanying drawings, and to letters of reference marked thereon, which form a part of this specification.

The object of this invention is to reduce the cost of constructing alarm-locks, and to increase the utility of the same.

It consists in the arrangements and combinations of parts substantially as will be hereinafter set forth, and finally embodied in the clauses of the claims.

Referring to the accompanying drawings, in which similar letters of reference indicate like parts in each of the several figures, Figures 1 and 2 are views of the interior of the lock, 25 showing different positions of the working parts; and Figs. 3, 4, 5, and 7 are detailed views of certain pawl-and-hammer mechanism for striking an alarm. Fig. 6 is a detailed elevation of a device for repressing a night 30 latch or bolt. Fig. 8, Sheet 2, is a plan of the exterior case, showing the same covering the bell, and a slot to receive the finger-piece of the night-latch; and Fig. 9 is an end view showing a similar slot through which a lever 35 projects, said lever being adapted to repress the hammer, so that an alarm will not be sounded when the door-knob is turned.

In said drawings, *a* is the lock-case, *b* is the shank of the door-knob, and *c* is a piece or 40 tumbler secured upon and working with said shank, and operating the alarm mechanism and the latch or bolt *d*. Said piece *c* or tumbler is provided with a toothed segment or 45 segmental ratchet, *e*, which engages a pawl, *f*, pivoted at *g* to the bed-plate. Said pawl carries the alarm-hammer *h*, and causes it to strike the bell when influenced by the spring *i*. The teeth of the segment engaging the 50 pawl throws said pawl, and with it the hammer, away from the bell until the pawl rides over the projections or ratchet-teeth and

is released. The spring *i* then causes the pawl to return and the hammer to strike a blow. The pawl is provided with a pivoted head, *j*, which, in the return motion of the 55 ratchet, gives under the influence of the ratchet-teeth, as indicated in Fig. 4, allowing said ratchet the return motion. Said pawl has a spring, *k*, thereon, which causes its head to return to its normal position after it has 60 been bent down by the returning ratchet-teeth of the segment. The latch *d* is actuated by the lug or finger *l* on the tumbler *c*, which engages a projection, *m*, on said latch, said latch sliding on the pin *m'* and between the lugs 65 *n n*, and being limited in its inward movement by the stop-lug *o*. The said latch or bolt, together with the night latch or bolt *q*, is thrown outward by the spring *r*, coiled around a stud, *s*, and having its opposite 70 extremities bearing against the said bolts or latches *d* and *q*, which are appropriately notched or recessed to receive the same. The night-latch slides in suitable guides or ways similar to those used in connection with the 75 latch *d*, and is repressed by a tumbler, *s'*, of peculiar construction, pivoted, as shown in Fig. 6, between the lock-plates *a*. Said tumbler has a finger, *t*, to engage a projection, *u*, on the night-latch, and a shank, *v*, projecting 80 through the case to receive a key. The shape of said shank may be varied to suit individual keys. To hold the said night-latch in a repressed position, there to remain during the day-time, I provide a finger-piece adapted 85 to be worked from the outside of the case, the shank *w* of which slides in the groove *w'* in the lock-case *a*, as in Fig. 8. Said shank *w* is adapted to be caught in the notches *w³ w⁴*, the former of which holds the latch or bolt in 90 a projected position, so that said lock cannot be opened from the outside even by the aid of a key, and the latter holds said bolt back in an inoperative position. To allow the shank to be readily raised or lowered into or from 95 said notches, I secure it to a piece, *w⁵*, Figs. 1 and 2, having a vibratory motion on but independent of the latch, as will be understood. The alarm mechanism is entirely inclosed by the lock-case *a*, as shown in Fig. 8, the bell 100 being covered by a shield in a degree conforming to the shape of said bell, and formed

- or cast integral with said case. By this construction the shield guards against the bell being muffled, and being thus prevented from sounding an alarm when the knob is turned.
- 5 The shield may be provided with openings, to allow the escape of the sound therethrough, said openings also being shown in Fig. 8. To hold the pawl back, so that when not needed it will be prevented from sounding an alarm,
- 10 I provide a latch or lever, a' , fulcrumed upon the case a at a^2 , and having a finger projection, a^3 , passing outward through the slot a^4 at the edge of the case a . The opposite extremity of said lever is bent or hooked, as at
- 15 a^5 , so as to strike the pawl or hammer thereon and hold it back, so that the ratchet will not engage with it to strike an alarm.
- Having thus described the invention, what I claim as new is—
- 20 1. In combination with the bell, hammer, and segmental ratchet, the jointed pawl, and a spring adapted to throw the hammer and pawl forward to strike an alarm, substantially as set forth.
- 25 2. In combination, in an alarm-lock, the knob-shank, the tumbler c , secured thereon, and having the lug l and segmental ratchet, the pawl operating the hammer, the latch d , and bell, all said parts being arranged and
- 30 operating substantially as set forth.
3. In combination with the slotted case a , the night-latch having the shank w , working in the slot therein, the spring r , the tumbler having a finger to engage with said latch, and a key-shank projecting through the case a , substantially as and for the purposes set forth. 35
4. In an alarm lock, the combination of the knob-shank, tumbler, latch d , segmental ratchet carried by said tumbler, the jointed pawl, the hammer secured to the head thereof, and the bell, all said parts being arranged and operating substantially as and for the purposes set forth. 40
5. In combination, in an alarm-lock, the jointed pawl carrying the bell-hammer, and a lever extending from said pawl to the outside of the case, and adapted to repress said pawl to a point free from engagement with the ratchet, said case, bell-hammer, bell, and segmental ratchet all arranged and operating 45 substantially as set forth.

In testimony that I claim the foregoing I have hereunto set my hand this 22d day of April, 1884.

JACOB WILLIAM KOHN.
